US0D1074034S

(12) **United States Design Patent** (10) Patent No.: **US D1,074,034 S**
(45) Date of Patent: ** May 6, 2025

(54) **LED DESKTOP LIGHT**

(71) Applicant: **JM Zengge Lighting Co., LTD,**
Jiangmen (CN)

(72) Inventors: **Xiaoxiong Feng**, Jiangmen (CN);
Bingta Lin, Jiangmen (CN)

(73) Assignee: **JM Zengge Lighting Co., LTD,**
Jiangmen (CN)

(**) Term: **15 Years**

(21) Appl. No.: **29/914,690**

(22) Filed: **Oct. 20, 2023**

(51) LOC (15) Cl. **26-04**

(52) U.S. Cl.

USPC **D26/104**

(57) **CLAIM**

The ornamental design for a LED desktop light, as shown and described.

DESCRIPTION

FIG. 1 is a front perspective view of a LED desktop light, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the LED desktop light, which form no part of the claimed design.

1 Claim, 8 Drawing Sheets
